UNITED STATES PATENT OFFICE.

JOSEPH STURIALE, OF NEW YORK, N. Y.

ARTIFICIAL-ORNAMENT-MAKING MACHINE.

Application filed December 28, 1921. Serial No. 525,462.

This invention has relation to the manufacture of millinery ornaments such as artificial flowers, fruits, etc., and has for an object to provide a machine by virtue of which an ornament such as a spherical body of thread or fibrous material may be fabricated upon the end of a flexible wire, the latter to constitute the stem of the product.

In addition to the foregoing this invention comprehends improvements in the details of construction and arrangement of parts to be hereinafter described and particularly set forth in the appended claims.

In the accompanying drawings in which similar and corresponding parts are designated by the same characters of reference throughout the several views in which they appear,

Figure 1 is a view in side elevation of a machine constructed in accordance with my invention.

Figure 2 is a view thereof in top plan.

Figure 3 is a detail transverse section taken on the line 3—3 of Fig. 1.

Figure 4 is a detail view of the wire feeding machine.

Figure 5 is a detail section taken on the line 5—5 of Figure 3; and

Figure 6 is a view of the product.

With reference to the drawings 10 indicates a table suitably supported and mounted thereon is a bearing 11 having a horizontal shaft 12 journaled therein upon which a pulley 13 is mounted. A wire feeding mechanism is provided consisting of a frame 14 which is carried by the bearing. A horizontal rod 15 is mounted in the frame and a weighted member 16 is slidable on the rod, a pin 17 depending from the member 16. A frame 18 located upon the table carries a reel of wire 19, one end of the wire passing through the frame 14 and entering a tube 20 which extends axially through the shaft 12. A wire gripping device is provided consisting of a jaw 21 slidably mounted upon the frame 14 and carrying a movable jaw 22 pivoted thereto, the wire passing between said jaws. A button 23 on the movable jaw is adapted to be engaged by the pin 17 for a purpose to be presently noted. A rod 24 is slidably mounted in the bearing 11 and an arm 25 depends from the jaw 21 for connection to said rod. A lever 26 fulcrumed to the table is also pivoted to the rod 24 whereby the latter may be shifted. The end of the

shaft 12 is formed with a transverse slot 27 into which the tube 20 extends and located at this point is a wire cutting device consisting of a pair of spring jaws 28 rotatable with the shaft and embracing the end of the tube 20, 60 being provided with cutting edges 29 which are adapted to mutually engage in shearing relation just beyond the end of the tube. One jaw carries a roller 30. A cup 31 surrounds the shaft 12 having a central opening 32 65 through which it projects and the inner periphery of the cup carries an abutment 33 to engage the roller 30. The opening 32 is larger than the shaft to permit movement and the cup is furthermore slotted to receive 70 fastenings 34 which are affixed to a box like mold carrier 35 mounted on the table. A spring 36 depending from a bracket 37 is attached to the cup to urge the latter in a raised position and a yoke and link connection 38 depends from the cup for attachment to a foot lever 39 to draw the cup downward at will. The mold consists of a half-block 40 mounted in the mold carrier and having a semi-circular recess 41 in its outer edge. 80 The end of the shaft 12 beyond the slot is reduced to form the spindle 42 which enters a channel in the half block 40 and exits into the recess 41. The other half-block 43 of the mold is movably mounted in the carrier and 85 is formed with a semi-circular recess 44 co-acting with the recess 41 when the blocks are together to define a circular perforation extending through the mold. It will be noted that the end of the spindle is at the center 90 of this perforation. The block 43 is shifted by means of a link 45 which connects the half-block to the upper end of a lever 46 fulcrumed to the carrier, the lower end of the lever being pivoted to the end of the rod 24. 95 A tray 47 is located beneath the carrier and is finely perforated at a point beneath the mold aperture. A receptacle 48 is mounted above the mold and is provided with a drain cock 49 which is intended to drip into the 100 mold aperture. A chute 50 located beneath the perforation of the tray leads into a receptacle 51 located beneath the table.

The operation.—The end of the wire is permitted to project beyond the end of the 105 spindle into the mold aperture as shown in Figure 2 and the end of a thread of fibrous material such as cotton is wound around the spindle a few times. Rotation of the shaft and pulley 13 through the medium of a belt 110

and source of power is now initiated and the thread guided by hand so as to wind up into a ball, the shape of the mold aperture lending assistance in this respect besides limiting the size of the ball and packing the fibrous material. During this operation a liquid adhesive such as a starch solution contained in the receptacle 48 is permitted to drip upon the winding ball of fibrous material which will cause the fibers to adhere and form a solid ball. When the winding operation is completed the thread is broken and the lever 26 shifted to the right against the tension of its spring, which will move the half-block 43 of the mold away from the other half block and at the same time move the jaws 21 and 22 of the wire feeding device to the right (Figure 2.)

It is obvious that as the jaws move to the right that the weight 16 will be moved therewith and owing to the connection of the upper jaw with the weight, the jaw will be raised releasing the wire. Thus the wire will not be moved during this operation. The foot lever 39 is now depressed which will lower the cup 31 causing the engagement of the abutment 33 with the roller 30, and by reason of the shaft rotation will move the shearing blades together upon the wire severing the same. The finished product, consisting of the ball and wire, is now withdrawn from the spindle by hand which is permitted owing to the fact that the mold is now in its opened position. The product is shown in Figure 6 of the drawing.

The lever 26 is now released and the spring will return the same to its normal position closing the mold and moving the dogs 21 and 22 to the left. As the jaws move to the left the button 23 carried by the upper jaw 22 will engage the pin 17 of the weight 16 which will move the dog to its wire gripping position and the weight will be returned. When the jaws move to the left the

wire will be carried therewith and be held 45 in position for the next operation.

The excess adhesive will fall through the perforated tray into the receptacle 51 so that it may be transferred back to the receptacle 48. 50

While I have illustrated and described my invention with some degree of particularity, I realize that in practice various alterations therein may be made. I therefore reserve the right and privilege of changing the form 55 of the details of construction or otherwise altering the arrangement of the correlated parts without departing from the spirit of the invention or the scope of the appended claims. 60

Having thus described my invention what I claim as new and desire to secure by United States Letters Patent is:—

1. In combination, means for supporting a wire, means for rotating said support axially, a mold to receive the end of the support and wire, means for shifting the wire longitudinally through the support, and means for cutting off the wire between the mold and shifting means. 65 70

2. In combination, means for supporting a wire, means for rotating the support, a mold enclosing the end of the support and having a separable part, a wire feeding means, a cutting off means and means for 75 operating the feeding means and for moving the mold part simultaneously.

3. In combination, a hollow rotating shaft to contain a wire, a cutting element consisting of shearing jaws one at each side of the wire and carried by the shaft and a movable abutment normally out of the path of movement of one jaw but adapted to be moved into engagement therewith, whereby said jaw is caused to move toward the other jaw 80 85 to sever the wire.

In testimony whereof I affix my signature.
JOSEPH STURIALE. [L. s.]
